UNITED STATES PATENT OFFICE.

THOMAS M. SIMCOE, OF ALLENtown, PENNSYLVANIA.

DESIGN FOR A GAME-BOARD.

SPECIFICATION forming part of Design No. 26,747, dated March 9, 1897.

Application filed December 29, 1896. Serial No. 617,408. Term of patent 3 $\frac{1}{2}$ years.

To all whom it may concern:

Be it known that I, THOMAS M. SIMCOE, of Allentown, in the county of Lehigh and State of Pennsylvania, have invented certain new and useful Improvements in Designs for Puzzles or Game-Boards; and I do hereby declare the following to be a full, clear, and exact description of the invention, such as will enable others skilled in the art to which it pertains to make and use it, reference being had to the accompanying drawings, which form part of this specification.

My invention relates to designs for game-boards, as illustrated in the accompanying drawings, in which—

Figure 1 is a perspective view, and Fig. 2 a vertical longitudinal sectional view.

My design for a game-board consists of a base or board A, having thereupon a plurality of curves or ribs B, one within the other, and

of different curvatures, as shown. The ribs at opposite ends of the board are placed with their open ends toward each other, and the board is provided with a correspondingly-shaped wall surrounding the larger curved ribs, as shown. Situated between the two series of curved ribs is a projection G, which, however, may be omitted, the characteristic of my design being the curved ribs situated as shown and described.

Having thus described my invention, what I claim is—

The design for a game-board substantially as herein shown and described.

In testimony whereof I affix my signature in presence of two witnesses.

THOMAS M. SIMCOE.
